RICHARD RALPH BROWN, OF BELVIDERE, ILLINOIS, ASSIGNEE OF ONE-HALF TO
WILLIS S. BROWN, OF BELVIDERE, ILLINOIS.

SPARK-PLUG.

1,098,093.

Specification of Letters Patent. Patented May 26, 1914.

Application filed November 4, 1911. Serial No. 658,515.

To all whom it may concern:

Be it known that I, RICHARD RALPH BROWN, a citizen of the United States, residing at Belvidere, in the county of Boone and State of Illinois, have invented certain new and useful Improvements in Spark-Plugs, of which the following is a full, clear, and exact specification.

This invention relates to spark plugs for 10 jump spark ignition systems or circuits, and it has for its object to provide a spark plug which will be economical to manufacture, simple in construction, durable, efficient in operation, and readily adjustable to various 15 conditions, as well as being of neat appearance.

With a view to the attainment of these ends and the accomplishment of certain other objects which will hereafter appear, 20 the invention consists in certain features of novelty in the construction, combination and arrangement of parts which will now be described with reference to the accompanying drawings and then more particularly pointing 25 ed out in the claim.

In the said drawings—Figure 1 is a longitudinal section of a spark plug embodying this invention; Fig. 2 is a detail elevation, partly broken away, of the gland; and 30 Fig. 3 is a similar view of a modified form of gland.

1 is a hollow member which is screw threaded on its exterior, as shown at 2, so that it may be screwed into the spark plug 35 aperture of an engine. This member 1 constitutes a housing for the porcelain insulator 3. The member 1 is formed with a shoulder 4, and the insulator 3 with a shoulder 5, and between these two shoulders is 40 interposed a gasket 7 adapted to make a gas-tight joint when the shoulders are pressed together. The insulator 3 is also formed with a tapering projection 8, which is surrounded by a gland 9 having a tapering feather edge 10, engaging the tapered 45 projection 8 and adapted to yield to irregularities in pressure resulting from irregularities in contour, or otherwise, when the gland 9 is forced over the tapered projection 8, the 50 gland 9 being formed of comparatively soft or yielding metal, so that it will also constitute a packing where it engages the projection 8. The gland 9 is screw threaded on its exterior and screwed into the screw 55 threaded interior of the member 1, as far

as may be necessary to securely hold the porcelain 3 in place and prevent leakage of gas.

The outer extremity of the gland 9 is formed with an electrode 11. This is preferably of the form of a bridge looping outwardly from the gland 9, and having a central aperture 12, into which the inner electrode 13 projects. This bridge electrode member 11 also constitutes a means whereby 60 the gland 9 may be readily screwed into place, and possesses the further important advantage of being susceptible of being formed of any desired length to adapt the spark plug to engines of different design, 65 it being often the case that the electrode must be extended farther inward with some engines than with others. Where this is the case the end has been accomplished in a measure by merely extending the member 1 and the electrode 13 inwardly the desired 70 extent. This, however, results in a long member 1, which is objectionable. In some cases instead of extending the member 1, a long extension or electrode has been secured 75 to the end thereof. This results in an objectionably long and flimsy electrode. With this invention, however, the member 1 may be used for engines of various designs, the glands 9 being formed with electrodes 11 of 80 different lengths, and the inner electrodes 13 being accordingly extended or shortened, 85 as may be necessary.

The extension 8 is formed with a socket 90 14 for the reception of a shoulder 15 on the stem 16 of the inner electrode, the stem being smaller than the shoulder 15, so as to form a seat for a gas-tight gasket 17. The stem 16 is held in place by nuts 18 as usual, or otherwise.

In the form of gland shown in Fig. 3, instead of using a soft yielding material for the inner end thereof, it is formed of elastic material, and the inner end is slotted at suitable intervals, as shown at 19, resulting in elastic tongues 20, which embrace the tapered projection 8 and hold it firmly and centrally while forcing the porcelain up to its seat against the shoulder 4. These tongues 20 yield to irregularities of pressure resulting from the porcelain and the gland being cut of true center while the gland is being screwed into place.

With a plug thus constructed it will be seen that all of the screw threads on the 110

member 1 are formed on one and the same end thereof, leaving the upper outer end entirely free from projecting nuts or glands. Consequently, the manufacture of the plug is considerably simplified and cheapened, because of the fact that all of the threading may be done by one operation, or one setting in the screw machine, making it possible also to form the shoulder 4, and finish 10 the interior of the member 1 without removing the latter from the machine.

What I claim is:

In a spark plug of the class described, the combination of a hollow open end body member having an inturned shoulder at its upper end and internal screw threads at its lower end portion, an insulator removably positioned in said hollow body member and having an enlargement abutting said shoulder, an electrode supported by said insu- 15 20

lator and extending beyond the lower end of said body member, and a one-piece hollow gland member adapted to be screwed into the lower end of said body member and having a tapered split upper end portion which 25 yieldingly engages and clamps said tapered enlargement against said shoulder and having an integral open-sided loop extension arranged in sparking relation to said electrode and provided with an aperture forming therewith a spark cap. 30

In testimony whereof I have signed my name to this specification, in the presence of two subscribing witnesses, on this 1st day of November A. D. 1911.

RICHARD RALPH BROWN.
